FOREIGN PATENT DOCUMENTS

WO DM/078193 * 4/2012

Primary Examiner — Dana Meyrow(74) *Attorney, Agent, or Firm* — Norris McLaughlin & Marcus PA(57) **CLAIM**

We claim the ornamental design for refill bottle with cap, as shown and described.

DESCRIPTION

FIG. 1 is a top, front perspective view of a first embodiment of a refill bottle with cap;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof;

FIG. 7 is a top, front perspective view of a second embodiment of a refill bottle with cap;

FIG. 8 is a front elevation view thereof;

FIG. 9 is a rear elevation view thereof;

FIG. 10 is a first side elevation view thereof;

FIG. 11 is a second side elevation view thereof; and,

FIG. 12 is a top plan view thereof.

The broken lines in the drawings illustrate the portions of the refill bottle with cap that form no part of the claim.

1 Claim, 12 Drawing Sheets(56)
